US0D1020119S

(12) **United States Design Patent** (10) Patent No.: **US D1,020,119 S**
(45) Date of Patent: ** Mar. 26, 2024

(54) **PET WATER FEEDER**

(71) Applicant: **Shaolang Ouyang**, Fujian Province (CN)

(72) Inventor: **Shaolang Ouyang**, Fujian Province (CN)

(**) Term: **15 Years**

(21) Appl. No.: **29/822,798**

(22) Filed: **Jan. 12, 2022**

(51) LOC (14) Cl. **30-03**

(52) U.S. Cl.

USPC **D30/132**

(57) **CLAIM**

The ornamental design for a pet water feeder, as shown and described.

DESCRIPTION

FIG. 1 is a front view of a pet water feeder, showing my new design;

FIG. 2 is a top plan view thereof;

FIG. 3 is a bottom plan view thereof;

FIG. 4 is a rear plan view thereof;

FIG. 5 is a left plan view thereof;

FIG. 6 is a right plan view thereof; and,

FIG. 7 is a perspective view thereof.

1 Claim, 7 Drawing Sheets
